BUILDING CONSTRUCTION

Herbert P. Weierman, Rydal, Pa.

Application October 21, 1943, Serial No. 507,065

7 Claims. (Cl. 20—95)

This invention relates to building construction and more particularly to provisions for quickly and easily securing building wall studs in position.

In the erection of interior partitions in new buildings, it is customary to employ studs vertically disposed at predetermined spaced intervals and secured at their ends to a beam or plate. In the erection of partitions in old buildings, the studs are usually secured to beams or plates running along the floor and along the plaster ceiling. In accordance with the present invention, provision is made for the rapid mounting or installing of the studs in spaced relationship in a manner which will require a minimum of time and which may be accomplished with unskilled labor. The construction in accordance with the present invention is particularly adapted for use in connection with prefabricated buildings.

The nature and characteristic features of the invention will be more readily understood from the following description, taken in connection with the accompanying drawing forming part hereof, in which:

Figure 1 is a perspective view illustrating the main features of the present invention;

Fig. 2 is a fragmentary front view illustrating the invention.

Fig. 3 is a fragmentary rear view;

Fig. 4 is a fragmentary bottom plan view; and

Fig. 5 is a diagrammatic view illustrating the invention and shortened both vertically and horizontally.

It will, of course, be understood that the description and drawing herein are illustrative merely, and that various modifications and changes may be made in the structure disclosed without departing from the spirit of the invention.

Referring more particularly to the drawing, wooden studs 10 of conventional type are illustrated, these studs 10 being adapted to be vertically disposed and spaced at predetermined intervals along the location at which the partition is to be erected. Preformed channel members 11 are provided, these being preferably used at the upper and lower ends of the studs 10 as indicated in Fig. 5.

The channel members 11 are preferably C-shaped in cross section, as illustrated in Fig. 1, and each has a flat portion 12 adapted to be disposed horizontally and secured in position by nails or other fastening means (not shown). The flat portion 12 is preferably less in width than the thickness of the finished partition after the

covering of lath and plaster, plaster board, or wood or other paneling has been applied. The flat portion 12 preferably has a width approximately equal to the width of the studs 10 although studs 10 of greater width may be employed therewith. The channel member 11 is illustrated in Figs. 1, 2 and 3 in the relationship which it occupies with respect to the upper end of a stud 10 although it will of course be understood that at the bottom of the stud 10 and along the floor the channel member 11 functions in the same manner. The channel members 11 have vertically extending side portions 13 and 14 and horizontally inturned flange portions 15 and 16. The channel member 11 is preferably preformed, in desired lengths, of relatively thin sheet material of adequate strength and thickness to give the stiffness required.

The side portion 13 is preferably cut away at intervals corresponding to the predetermined locations at which the studs 10 are to be mounted, which intervals may, for example, be at sixteen inch centers commonly employed for mounting studding. The length of the cutaway portions 13 along the side portions 13 is preferably greater than the thickness of the studs 10. The other side portion 14 is preferably continuous and uninterrupted, as illustrated in Figs. 3 and 4.

The flange portion 15 is cut away to provide a slot at the same spaced intervals, the slot preferably having two opposed tapered edges 17 which are spaced, at their innermost terminals, a distance slightly less than the thickness of the studs 10 to exert a wedging and gripping action on the studs 10 as hereinafter explained.

The flange portion 16 is also cut away to provide a slot at the same spaced intervals. The slot has tapered edges 18 which are spaced, at their termination at the side portion 14, a distance slightly less than the thickness of the studs 10 to permit the wedging of the studs 10 therebetween. The studs 10 which are employed in building operations are not always of the same thickness but the provision of the edges at 17 and at 18 permits accommodating studs 10 of varying thickness. Variation of the width of the studs 10 within reasonable limits is also accommodated.

In the use of the present invention the upper and lower channel members 11 are fixed in place in any desired manner, such for example as driving nails through the horizontal portions 12 into the ceiling beams or through the plaster ceiling into the ceiling beams, and into the floor or floor beams. When a pair of channel members 12 have

thus been placed in position the studs 10 are then driven into place. The parallel side faces of the studs 10 are forced into wedged relationship with respect to the edges 18, which edges 18 may and preferably do bite into the parallel faces for a short distance. The studs 10 may, if desired, be driven in so that they engage the side portion 14. The studs 10 are at the same time brought into gripping engagement with the edges 17 which also preferably bite into the parallel faces of the studs 10. The studs 10 are firmly gripped and held in position, are restrained against movement in a direction along the channels 11, and are restrained against withdrawal. If desired, however, the studs 10 may be mounted in the channel members 11 and the assembly put in place and held by nailing through the horizontal portions 12. It will thus be seen that the studs 10 may be quickly and easily mounted in position and are firmly held in fixed relationship for the completion of the partition.

I claim:

1. In building construction, a vertical stud having parallel faces, and a channel member having a flat portion, side portions angularly disposed with respect to said flat portion and flanges extending from said side portions and parallel to said flat portion, said flanges having slots with opposed marginal edge portions of said slots for gripping engagement with a pair of the faces of said stud.

2. In building construction, a vertical stud having parallel faces, and a channel member having a horizontal portion, vertical side portions connected to said horizontal portion, and horizontal flanges connected to and extending inwardly from said side portions and parallel to said horizontal portion, said flanges having slots therein with opposed marginal portions of said slots for gripping engagement with a pair of the faces of said stud.

3. In building construction, a vertical stud having parallel faces, and a channel member having a horizontal portion, vertical side portions and horizontal flanges extending inwardly from said side portions, at least one of said flanges having opposed tapered edge portions for gripping engagement with a pair of the faces of said stud.

4. In building construction, a vertical stud having parallel vertical faces, a channel member having a horizontal portion, vertical side portions, and horizontal flanges extending inwardly from said side portions and parallel to said horizontal portion, one of said side portions having a slot for the reception of the stud, the flange adjacent said side portion having a slot with marginal edges for gripping engagement with vertical faces of the stud, and the other flange having a slot with marginal edges for engagement with vertical faces of the stud.

5. In building construction, a vertical stud having parallel faces, a channel member having a horizontal portion, vertical side portions, and horizontal flanges extending inwardly from said side portions, one of said side portions having a slot for the reception of the stud, the flange adjacent said side portion having nonparallel edges for engagement with a pair of parallel faces of the stud.

6. In building construction, a vertical stud having parallel faces, a channel member having a horizontal portion, vertical side portions, and horizontal flanges extending inwardly from said side portions, one of said side portions having a slot for the reception of the stud, the flange adjacent said side portions having a slot with tapered edges for gripping engagement with faces of the stud and the other flange having a slot with tapered edges for wedging engagement with faces of the stud.

7. In building construction, a vertical stud having a pair of parallel vertical faces, a channel member having a horizontal portion, vertical side portions, and horizontal flanges extending inwardly from said side portions, one of said side portions having a slot for the reception of the stud, the flange adjacent said side portion having a slot with tapered edges closer together at their innermost terminals for gripping engagement with said faces of the stud and the other flange having a slot with tapered edges closer together at the contiguous side portion for wedging engagement with said faces of the stud.

HERBERT P. WEIERMAN.
